Specification for Design.

Patented Feb. 11, 1913.

Application filed May 24, 1912. Serial No. 699,535. Term of patent 7 years.

To all whom it may concern:

Be it known that I, LEONARD L. FERGUSON, a citizen of the United States, residing at Chicago, in the county of Cook and State of Illinois, have invented a new, original, and ornamental Design for a Casing for a Pneumatic Cleaner, of which the following is a specification, reference being had to the accompanying drawings, forming part thereof.

The figure is a perspective view of a casing for a pneumatic cleaner, showing my new design.

I claim:

The ornamental design for a casing for a pneumatic cleaner, as shown.

In witness whereof, I have hereunto subscribed my name in the presence of two witnesses this 21st day of May, 1912.

LEONARD L. FERGUSON.
